UNITED STATES PATENT OFFICE

146,951

DESIGN FOR A BATHER'S COSMETICS BOX OR SIMILAR ARTICLE

Ervin B. Steinberg, Milwaukee, Wis.

Application July 6, 1946, Serial No. 131,348

Term of patent 7 years

(Cl. D86—10)

To all whom it may concern:

Be it known that I, Ervin B. Steinberg, a citizen of the United States, residing at Milwaukee, in the county of Milwaukee and State of Wisconsin, have invented a new, original, and ornamental Design for a Bather's Cosmetics Box or Similar Article, of which the following is a specification, reference being had to the accompanying drawing forming a part thereof, and in which:

Fig. 1 is a top plan view of a bather's cosmetics box or similar article, showing my new design;

Fig. 2 is a side elevation of the same; and

Fig. 3 is a bottom plan view of the same.

My design is characterized by the portions shown in full lines.

I claim:

The ornamental design for a bather's cosmetics box or similar article, substantially as shown and described.

ERVIN B. STEINBERG.
